UNITED STATES PATENT OFFICE.

EDGAR A. WALZ, OF NEW YORK, N. Y.

HEAD-PROTECTOR.

1,004,507.

Specification of Letters Patent. Patented Sept. 26, 1911.

Application filed March 21, 1911. Serial No. 616,002.

To all whom it may concern.

Be it known that I, EDGAR A. WALZ, citizen of the United States, residing at New York, in the county of New York and State of New York, have invented certain new and useful Improvements in Head-Protectors, of which the following is a specification.

This invention relates to a head covering or protector, and has for an object to provide a transparent protector supported upon the head and having its sides spaced from the head so as to hold off mosquitos, flies, bees, and other insects, as well as to protect the head from all objects moving in the air.

Another object of this invention is to provide a protector of this character with a flexible support within its upper end adapted to rest upon the head of the wearer and carry the protector, the support being of such peculiar shape as to space the sides of the protector from the head.

A further object of this invention is to peculiarly form a head protector whereby it may be closed at its lower end about the neck of the wearer to exclude insects and the like to be kept from the head.

The invention still further contemplates a protector which may be folded into comparatively small space for transportation and storing away, a protector which is of simple construction and light in weight, and one which can be quickly applied to the head or removed therefrom to produce a thoroughly practical and efficient device.

For a full understanding of the invention and the merits thereof and also to acquire a knowledge of the details of construction, reference is to be had to the following description and accompanying drawings, in which:

Figure 1 is a perspective view of the improved protector as applied to the head; Fig. 2 is a transverse section taken through the protector and looking down through the same; Fig. 3 is a detail sectional view of the upper end or dome of the protector; Fig. 4 is a detail sectional view taken through one side of the protector.

Corresponding and like parts are referred to in the following description and indicated in all the views of the drawing by the same reference characters.

Referring to the drawing the improved protector comprises a crown or dome formed

of a frame having a base ring 10 carrying a plurality of arcuate rods 11 spaced from one another and extending up to a connecting ring 12.

Within the crown or dome is disposed a support or head engaging member of a flexible nature, the same preferably comprising a plurality of crossed strips 13 stitched together at their crossed central portions and having their ends stitched or otherwise suitably attached to the sides of the base ring 10. The flexible strips 13 are loose within the base ring 10 so as to project up into the dome or crown when the strips rest upon the head to support the ring. The supporting strips merge at their outer ends into connecting strips 14 depending from the sides of the base ring 10 and supporting in vertical spaced relation a plurality of rings 15. The lowermost or bottom ring 15' is slightly reduced in size for engagement beneath the chin, and carries a plurality of spirally disposed arms 16 of a spring nature, the same extending in one direction and supporting upon their lower ends a turned-over binding strip 17 providing a channel about the lower end of the protector for the reception of a draw-string 18. The draw string 18 is employed in contracting the lower end of the protector about the neck of the wearer in order to exclude insects and the like. The lower extremities of the connecting strips 14 are attached to the sides of the bottom ring 15' and are suitably secured to the intermediate rings 90 for holding the same in position.

A flexible covering 19 of netting of small mesh is disposed over the crown and extends down about the rings 15, and has its lower end secured to the binding strip 17 for the purpose of entirely closing the protector. The covering 19 is attached to the crown and to the flexible connecting strips and rings so that when the protector is folded the cover will collapse and lie in between the rings 15.

In the application of the improved protector the head is inserted up through the rings 15, the flexible support engaging against the top of the head and being spaced down from the crown. The rings 15 fall about the head and are of such size as to space the covering 19 out from the head to hold off the insects coming against the protector.

Having thus described the invention, what is claimed is:

A head protector comprising a frame, a covering mounted thereon, a ring forming the lower portion of the frame, spirally disposed resilient arms attached at their outer ends to the said ring, said covering extending along the outer sides of said arms, a binding strip connecting the inner ends of

the arms together, and means for gathering 10 and holding said strip.

In testimony whereof, I affix my signature in presence of two witnesses.

EDGAR A. WALZ. [L. s.]

Witnesses:

JOHN A. SAMBORN,
THOS. C. WALZ.
